TRANSMITTER MOUTHPIECE

Filed Dec. 30, 1922

Inventor:
Harold F. Dodge.
by J. L. Palmer Atty

UNITED STATES PATENT OFFICE.

HAROLD F. DODGE, OF NEW YORK, N. Y., ASSIGNOR TO WESTERN ELECTRIC COMPANY, INCORPORATED, OF NEW YORK, N. Y., A CORPORATION OF NEW YORK.

TRANSMITTER MOUTHPIECE.

Application filed December 30, 1922. Serial No. 610,000.

This invention relates to transmitter mouthpieces and the object is the improvement of the quality and the articulation from a transmission standpoint.

5 In accordance with the general features of this invention there is provided a mouthpiece which will offer a minimum external reflecting surface to impinging sound waves and will prevent the emphasis of the hissing 10 and the explosive sounds in speech, which involve windage, without loss in articulation.

In its preferred form the mouthpiece is in the form of a shell having a plane face provided with a plurality of elongated slots or 15 openings tapered inwardly, said slots being so positioned that planes bisecting the slots along their greatest dimensions are parallel to the average direction of talking.

20 Referring to the drawing;

Fig. 1 shows a side view of a hand set, part in section, having a transmitter mouthpiece embodying the invention;

Fig. 2 is a plan view of the mouthpiece;

25 Fig. 3 is an enlarged section showing the shape of the openings in their preferred form;

Figs. 4, 5 and 6 show modifications in the shape of the openings.

30 On the handle 3, there is mounted at one end a receiver 4 of any suitable type and on the opposite end a transmitter 6 which is provided with a mouthpiece 7 preferably of phenol plastic compound, having an annular portion 9 and a perforated face 14 preferably integral therewith, oblique to the axis of said annular portion. The annular portion 9 may be provided with a plurality 35 of slots 10 through which screws 11 secure the mouthpiece 7 to the transmitter case 17.

40 The slots 10 are preferably counter sunk at one end to receive the heads of the screws 11. The perforations in the face 14 are formed by parallel bars 12, one side, 13, of each bar 45 being preferably substantially perpendicular to the face 14 and the opposite side 15 being oblique thereto. The sides of adjacent bars form long, narrow openings having converging walls with the planes bisecting the 50 openings along their greatest dimensions parallel to each other and to the average direction of sound propagation, which ar-

rangement minimizes the windage effects of hissing and explosive sounds. Joining the bars 12 is a rib 16 for the purpose of reinforcement when the mouthpiece is made of phenol plastic compound or similar materials. When the mouthpiece is made of metal, such as brass or aluminum, this reinforcing member may be omitted.

55 What is claimed is:

1. A transmitter mouthpiece having a grid formed of a plurality of parallel bars forming openings of greater dimensions at one side than at the other.

60 2. A transmitter mouthpiece having a plane face of uniform thickness, said face comprising a plurality of laterally elongated openings, said openings being of larger dimensions at the top than they are at the bottom.

65 3. A transmitter mouthpiece having a grid formed by parallel bars having oppositely diverging sides, said bars so disposed that their adjacent sides form long, narrow 70 apertures having converging walls.

75 4. A transmitter mouthpiece having parallel bars, the adjacent bars forming long, narrow openings with converging walls, the planes bisecting said openings along their greatest dimensions being parallel to each 80 other and extending in the direction of sound propagation.

85 5. A transmitter mouthpiece comprising a grid having long, narrow bars, one side of each bar being substantially perpendicular to the face of said grid and the opposite side oblique thereto, adjacent bars thereby forming long narrow openings having converging walls.

90 6. In a transmitter, a diaphragm and a mouthpiece having a grid face oblique to said diaphragm, said grid being formed by a plurality of parallel bars having diverging sides.

95 7. A transmitter, a diaphragm, a mouthpiece having an annular portion and a grid portion oblique thereto, said grid portion being formed by a plurality of parallel bars having diverging sides, the sides of adjacent bars forming openings, the planes bisecting the openings along their greatest dimensions being oblique to the face of said grid.

8. In a telephone hand set, a transmitter and a mouthpiece for said transmitter having a plurality of bars transverse to the medial plane of said hand set, said bars having diverging sides forming slots having parallel axes in the direction of sound propagation.
9. In a telephone hand set, a transmitter comprising a mouthpiece having a plurality

of bars transverse to the medial plane of said hand set, and forming openings therein having opposite diverging sides oblique to the face of said mouthpiece.

In witness whereof, I hereunto subscribe my name this 28th day of December A. D., 1922.

HAROLD F. DODGE.
